(74) Attorney, Agent, or Firm—Price Heneveld Cooper DeWitt & Litton

(57) **CLAIM**

The ornamental design for a seating unit, as shown and described.

DESCRIPTION

FIG. 1 is a perspective view of a seating unit showing my new design;

FIG. 2 is a right side elevational view thereof;

FIG. 3 is a left side elevational view thereof;

FIG. 4 is a rear elevational view thereof;

FIG. 5 is a top view thereof;

FIG. 6 is a front elevational view thereof; and,

FIG. 7 is a bottom elevational view thereof.

The dashed lines in FIGS. 1-7 show the environment and do not form a part of the design sought to be patented.
